UNITED STATES PATENT OFFICE.

CHARLES A. WARREN, OF WATERTOWN, CONNECTICUT.

DESIGN FOR WHIP-RACK.

Specification forming part of Design No. **6,216**, dated October 22, 1872.

To all whom it may concern:

Be it known that I, CHARLES A. WARREN, of Watertown, in the county of Litchfield and State of Connecticut, have invented a new Design for Whip-Rack; and I do hereby declare the following, when taken in connection with the accompanying drawing, to be a full, clear, and exact description of the same, and which said drawing constitutes part of this specification and represents a top view of the whip-rack.

This invention relates to a design for device for hanging whips; and consists in the peculiar configuration of the holder, shown in the accompanying illustration, and as more fully hereinafter described.

The device is in circular form, with radial slits for various sizes of whips; so that the whips may be hung therein either by the butt or tip; and the holder is provided with a screw, as seen in the illustration, by which it can be attached to the wall.

I claim as my invention—

The design for whip-rack, as shown in the accompanying illustration and as herein described.

CHAS. A. WARREN.
